UNITED STATES PATENT OFFICE

FRANZ A. BOEDTCHER, OF BERGENFIELD, NEW JERSEY, ASSIGNOR TO OTIS ELEVATOR COMPANY, OF JERSEY CITY, NEW JERSEY, A CORPORATION OF NEW JERSEY

MAGNETICALLY OPERATED SWITCH

Application filed November 22, 1926. Serial No. 149,886.

This invention is a magnetically controlled switch particularly adapted for use in connection with the signalling circuits of elevators and adapted to be automatically operated by the passage of the magnet carried by the elevator cage.

The switch of this invention embodies a pivoted arm adapted to be mounted in close proximity to the path of a permanent or electromagnet, so that as the magnet moves along its predetermined path, it will operate the arm as it passes the same.

In practice, the switch arm to which I have referred is generally in the form of a rocker pivoted intermediate its ends and rocking movement is imparted to this switch arm during the passage of the magnet in proximity thereto. When it is borne in mind that elevator cages travel at relatively high speed, 20 not infrequently up to 700 or 800 feet per minute, it is apparent that the interval, during which the magnet is in proper cooperative relation to the switch arm, is relatively short, and the arm must be operated during 25 this interval in order to function.

My experience coupled with extensive experiments has shown that if the magnet is made of sufficient power to operate such a switch arm at high speeds, there is a marked 30 tendency on the part of the switch arm to rebound after operation. This is due to several reasons. For example, the switch arm necessarily embodies more or less inertia, which must be overcome before movement 35 can be imparted thereto. If a magnet of sufficient power is provided to rapidly overcome this inertia, the movement of the switch arm is very rapid, and if it is brought to a sudden stop, rebound is almost sure to occur 40 unless some appropriate means is provided to lock the parts against such rebound.

The object of the present invention therefore is to provide a switch of the character described which may be efficiently and economically manufactured and which may be used with a high degree of efficiency in conjunction with rapidly moving elevators and without fear of faulty operation due to rebound or otherwise.

Speaking generally, the switch of this in-

vention embodies a pivoted arm which is preferably mounted to rock upon a pivot intermediate its ends. Either one or both ends of the arm carry one or more movable electrical contacts, which are adapted to cooperate with relatively fixed contacts mounted on a suitable adjacent stationary support. These so-called relatively fixed contacts are preferably formed so that they will cooperate with the movable contacts in a yieldable manner to so cushion the operation of the switch arm as to substantially lock the arm against rebound.

For cars moving at relatively high speeds, this cooperative relation between the fixed and movable contacts will serve to eliminate rebound, but in the case of cars moving at very rapid speeds, a further expedient is preferably associated with the switch arm and consists in positioning a link or links beyond the free end or ends of the switch arm and pivotally associating said links with the arm and with a suitable firm support. The purpose of the links to which I have referred is to extend the length of time during which the switch arm is responsive to the pull of the magnet and also to so constitute the structure that the magnetic force exerted on said arm will be gradually decreased instead of suddenly discontinued.

In practice, the links may be used exclusively of the spring contact arrangement referred to or vice versa, but the best results are obtained when both of these expedients are employed in the construction of the switch. A switch thus constructed will not rebound irrespective of the magnetic force applied thereto or irrespective of the speed at which the associated elevator is operating.

Features of the invention, other than those adverted to, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a front view of a switch embodying the present invention.

Figure 2 is a side elevation of the switch with one fixed contact removed and the 5 pivotal connection of the upper link shown in section in the interest of clearness.

Figure 3 is a fragmental section on the line 3—3 of Fig. 1.

Figure 4 is a fragmental section on the 10 line 4—4 of Figure 1.

Figure 5 is a central longitudinal section through the switch arm at that point in its length which carries the movable contact, this view illustrating details of said contact; 15 and,

Figure 6 is a section on the line 6—6 of Figure 1.

Referring to the drawings, 1 designates a 20 suitable supporting plate. Mounted about midway of the length of the plate is a bracket 2 which carries a laterally extending pin 3. This pin passes through an arm 4, and a cotter pin 5 is provided to preclude disengagement of the arm from the pin 3.

25 The arm 4 constitutes the switch arm of this invention and is adapted to be rocked on the axis of the pin 3 during the passage of an electromagnet M in proximity to and longitudinally of the rocker 4.

30 It will be noted that the rocker 4 is bent at its center, so that, when in either of its extreme positions, one end portion of the rocker will be substantially parallel with the path of travel of the magnet. The advantage 35 of this arrangement is that it permits the magnet to be set closer to the rocker than if the rocker were made straight. The extent of pivotal movement to which the rocker is susceptible is limited by a stop ring 6 into which 40 extends a cushioning button 7 preferably sheathed with rubber and carried by one arm of the rocker, as shown in Figures 1 and 2.

45 Associated with either one or both of the opposite ends of the rocker are one or more movable contacts. Any appropriate number of such contacts may be employed and they may be mounted on one end of the rocker to the exclusion of the other end thereof if desired. For the purpose of illustration, however, I have shown one movable contact associated with each end of the rocker. This contact is in the form of a pin 8 which extends directly through the rocker and projects beyond the opposite side thereof. The detail of the mounting of the pin is shown in Fig. 5. Here the rocker 4 is 50 shown as perforated to receive an insulating bushing 9. Insulating discs 10 are positioned against the opposite faces of the rocker and an eyelet 11 passes through the bushing and is flanged at its opposite ends over washers 12. The eyelet provides a bearing through which the contact pin extends and in which said pin is floatably supported 55 while the pin is insulated from the rocker 4.

Each pin 8 is adapted to cooperate with contacts positioned adjacent the opposite lateral faces of the rocker, and with which the opposite ends of the pin are adapted to contact to cause the pin to function after the manner of a bridge piece for feeding the current between the contacts. The contacts at one side of the rocker are rigid, and as shown in Figure 6, there are two of them 14 carried by a suitable insulating bracket 15 secured by means of screws 16 to the supporting plate 1. The contact at the other side of the rocker is in the form of a spring plate 17 which is returned upon itself.

60 One end of the plate is secured to an up-standing bracket 18 of conducting material. This bracket is secured by means of screws 19 to an insulating plate 20 which is, in turn, mounted upon a supporting plate 1. The other end of the spring plate extends into engagement with the contiguous end of the pin 8, with sufficient pressure to maintain the opposite end of the pin at all times in engagement with one or the other of the contacts 14. The employment of a spring plate 65 is of importance and the shaping of the plate is material. For example, it will be noted from Figs. 3 and 4 that the free end of the plate is wider in a vertical direction as viewed in Figs. 3 and 4, than the end of the 70 plate which is secured to the bracket 18, and that said plate is moreover longitudinally slotted at 21, so that the relatively long free end is supported upon relatively narrow resilient arms 22. This relatively long free end to which I have referred is designated 23 in Figs. 3 and 4 and constitutes the working end of the contact, since it is over the face of this portion of the plate that the pin is caused to slide as the rocker is tilted from 75 one position to the other.

80 By the formation of the plate as specified, it will be apparent that when the rocker is tilted into its terminal positions, the working head 23 will be tilted, as shown in Fig. 4. That is to say, when the pin is in one terminal position, as shown in full lines, it will tilt the head 23, as shown in full lines, whereas when the pin is in the other terminal position shown in dotted lines, the head will be 85 similarly tilted as shown in dotted lines. To move from one of these positions to the other, the pin will be forced to travel along the inclined surface of the head 23 until it reaches substantially the center of the head 90 and upon further movement of the pin in the same direction, the head will tilt into the opposite position and the pin will readily slide down, as it were, into its other terminal position. With this construction, therefore, 95 the maximum pressure which is brought to bear by the head upon the pin will be at the center position for it is here that the pressure plate is placed under the greatest pressure or retracted to the greatest extent.

It therefore follows that by this arrangement, the movement from one terminal position into the center position must be accomplished by a positive operation of the pin and such movement cannot be inadvertent. It therefore follows that the structure which I have described will resiliently maintain the rocker in either of its terminal positions and preclude rebound of the rocker after operation by the magnet M.

In practice, I preferably use the spring plate which I have described, but it will be apparent to those skilled in the art that the presentation of inclined surfaces to the movable contact may be accomplished by other than the specific means described, and the present invention is therefore not limited to this illustrative form of the invention.

It will of course be understood that in practically carrying out the invention, as thus far described, the circuits to be controlled by the switch are connected to the contacts 14 and 17 by associating suitable binding posts with these contacts. These circuits may form part 25 of signal setting or resetting circuits, or may, in practice, constitute any other circuits, which it is desired to control by a switch of the character herein described.

To the opposite ends of the rocker 4 are pivoted links 24, the distant ends of which are supported on suitable brackets 25 through pivotal connections 26, shown in Figure 2 as capable of permitting longitudinal movement of the links 24. The opposite ends of the 35 rocker are shown as bifurcated to provide a convenient pivoted connection for the links in question, but any other suitable construction would serve the purpose.

In practice, the rocker 4, as well as the links 24 are of metal capable of being attracted by a permanent or electromagnet, and these parts are adapted, in the operation of the switch of this invention, to function as the armature or armatures of the electromagnet M associated therewith. Thus, when the magnet is at any point between the pivot 3 and one of the pivots 26, it will attract the intervening portion of its armature to move the rocker into a corresponding position. If, however, the magnet is moved to the opposite side of the pivot, the other portion of this armature will be attracted and the position of the rocker will be reversed. If it be assumed, therefore, that the magnet is traveling in an upward direction from the full line position in Figure 2, it will be attracting all that portion of the rocker 4 below the pivot 3, as well as the lower link 24.

As a result, the rocker will be held in the position shown in this figure until the magnet has moved to a position above the pivot 3 and into substantially this position shown in dotted lines. It will then proceed to retract that portion of the armature above the pivot 3 and 65 will move the armature into a reversed posi-

tion. The exact point in the travel of the magnet M where this reversal will take place will depend largely upon the power of the magnet and the speed at which it is moving. If it is moving at a very high speed, it may 70 pass a considerable distance along the upper arm of the rocker before the inertia of the rocker is overcome sufficiently to bring about a shifting thereof. However, the rocker cannot rebound even though the resilient plates 75 17 are insufficient to overcome this tendency, because the magnet will continue after it leaves the upper end of the rocker to exert a pull upon the upper link 24 and this pull will become of less and less force in the holding of the rocker against rebound as the magnet nears the upper pivot 26. When it reaches the pivot, the effective pull on the link will cease, but by this time the period of rebounding 80 tendency has passed.

It therefore appears that the present invention embodies two safeguards against rebounding. Operating conjointly, the links 24 and the spring plates 17 will positively preclude rebound under the most trying conditions in the operation of high speed elevators. If the switch is to cooperate with elevators adapted to run at lower speeds, either of the expedients to which I have referred may be used to the exclusion of the other, but if either is to be omitted, I prefer to omit the links 24 and retain the spring plates 27 since they function with high efficiency and preclude inadvertent shifting of the rocker in directions adverse to the operations of the magnet and frictionally and resiliently hold the parts in the positions to which they have been set by the magnet.

I do not wish to be understood, however, as minimizing the importance of the employment of the links 24. The use of these links of which there may be more than two, without departing from the invention, enables me to extend the length of the magnet armature without increasing the distance between the magnet and its armature. That is to say, if the rocker arms were made to extend to the distant ends of the links and form a rigid construction, the magnet would have to be placed a relatively great distance away from its armature and a magnet of many times the strength possible to use under the construction described would have to be employed, and even then the operation would not be dependable. The employment of a yieldable extension of the armature is therefore highly important from a practical standpoint.

The use of the spring plate which causes the end of the pin to travel over the inclined surface of the head 23 has an advantage other than that hereinbefore referred to, namely, that inherent in the rolling operation of the pin. In practice, it is found that when the pin traverses the inclined surface of the head 125 130

23, it partakes of a rolling movement, which maintains the contacting surfaces between the pin and the plate and the pin and the contacts 14 smooth and bright and renders the pin self cleaned. This obviates the necessity of frequent inspection and manual cleaning.

10 The foregoing detailed description sets forth the invention in its preferred practical form. I am aware, however, that the shape of the several parts which I have described, as well as details of construction may be varied without departing from the spirit of this invention and the invention is therefore to be considered as fully commensurate with 15 the appended claims.

Having thus fully described the invention, what I claim as new and desire to secure by Letters Patent is:

20 1. In an assembly of the character described, a magnetically operable switch comprising a movable current switching member, a magnet mounted to travel past the current switching member and in proximity thereto, said magnet causing movement of said member to an operated position as it comes opposite thereto, and means for precluding rebound of said member from said operated position as the magnet passes beyond said member.

25 2. In an assembly of the character described, a magnetically operable switch comprising a movable current switching member, a magnet mounted to travel past the current switching member and in proximity thereto, said magnet causing movement of said member to an operated position as it comes opposite thereto, and means operable independently of magnetic force from the magnet, to preclude rebound of said member from said operated position as the magnet passes beyond said member.

30 3. In an assembly of the character described, an electromagnet mounted to travel along a predetermined path, a movable current switching member positioned in proximity to said path and adapted to serve as the armature of said magnet, said magnet attracting said member to an operated position as it comes opposite thereto during its travel, and means for maintaining the current switching member in the position to which it is attracted by said magnet after the magnet has passed beyond said member, without 35 rebound as the magnet leaves the member.

40 4. In an assembly of the character described, a magnet mounted to move along a predetermined path, a movable current switching element positioned adjacent said path and functioning as an armature for said magnet to be moved thereby, while the magnet is passing said member, and means operatively connected to said member and operable by the magnet to maintain the member in the 45 position into which it has been moved by

the magnet, after the magnet is passed beyond said member.

5. In an assembly of the character described, a magnet mounted to travel along a predetermined path, a current switching member operable by said magnet while the magnet is passing said member, and means operable by the magnet after it has passed said member to maintain the member in the position in which the magnet has operated it. 70

6. In an assembly of the character described, a magnet mounted to travel along a predetermined path, a rocker mounted to pivotally move on an axis extending transversely of the path of travel of the magnet, a current switching device mounted on said rocker and movable thereby into and out of cooperation with relatively fixed contacts, and extending members pivotally associated with the rocker and extending beyond the ends thereof to provide prolonged cooperation between the rocker and the magnet. 80

7. In an assembly of the character described, a magnet mounted to travel along a predetermined path, a current switching member embodying a rocker positioned in proximity to the path of travel of the magnet and functioning as the armature of the magnet, and members pivoted to and extending beyond the ends of the rocker and adapted to also function as armatures for the magnet, whereby the cooperative relation between the magnet and rocker is prolonged. 85

8. In a magnetically operable switch, a member mounted to rock, a contact carried by said member and movable thereby between two well defined termini, a relatively fixed resilient element bearing at all times against the contact of the pivoted member and presenting to said pivoted member an inclined surface when said contact is at either of its termini. 95

9. In a magnetically operable switch, a pivoted member mounted to rock, a movable contact carried by the pivoted member, fixed contacts adapted to engage with and be traversed by said movable contact as the pivoted member is moved from one to the other of its termini, and resilient pressure means bearing against a movable contact to force it in the direction of the fixed contacts, said resilient pressure means embodying an operating head tiltable in a direction of travel of the movable contact and resiliently impelled into such tilted position to present an inclined path to the contact when the latter is in either of its terminal positions. 100

10. In a magnetic switch, a pivoted member constituting an armature and carrying thereon at least one contact, a plurality of relatively fixed contacts with which the movable contact is adapted to cooperate, and a spring plate bearing against the movable contact at all times to force it into cooperative relation with the fixed contacts, the resiliency 110

of said plate serving to present an inclined surface to the movable contact when said contact is at either of the termini of its travel.

11. In a magnetic switch, a pivoted member constituting an armature and carrying thereon at least one contact, a plurality of relatively fixed contacts with which the movable contact is adapted to cooperate, a pressure head bearing against the movable contact at all times to force it into cooperative relation with the fixed contacts, and means for supporting said pressure head resiliently to cause it to present an inclined surface to the movable contact when said contact is at either of the termini of its travel.

12. In a magnetically operable switch, a movable switch arm, a contact carried by said arm, and a relatively fixed contact with which the movable contact is adapted to cooperate, said contacts being formed to present an inclined surface against the movement of one contact away from the other.

13. In a magnetically operable switch, a switch arm carrying a movable contact, a relatively fixed contact mounted to yieldably cooperate with the movable contact, said fixed contact being formed to present to the movable contact an inclined surface to retain the switch arm against inadvertent movement.

14. In a magnetic switch, a pivoted member constituting an armature, a current bridge piece carried by said member extending parallel to the axis of pivotal movement of the member and mounted for longitudinal movement with the opposite ends of the bridge piece exposed, a plurality of fixed contacts spaced apart and between which the bridge piece is adapted to be moved through movement of said member, at least one of said relatively fixed contacts being resilient whereby the bridge piece is caused to engage both contacts simultaneously and constitute a current bridge therebetween.

15. In an assembly of the character described, a magnetically operable switch comprising a movable current switching member, a magnet mounted to travel apass the current switching member and in proximity thereto for the purpose of operating said member, and magnetically operable means for precluding rebound of said member when it is operated by the magnet.

In testimony whereof I have signed the foregoing specification.

FRANZ A. BOEDTCHER.
